SIGN

Herbert A. Hoag, Tecumseh, Mich.

Application August 17, 1944, Serial No. 549,870

3 Claims. (CL 40—143)

This invention relates to signs and more particularly to that type of sign wherein the arrangement of letters or characters thereon may be changed at the will of the exhibitor.

A primary object of this invention is the provision of a sign having interchangeable letters, which letters may be changed with a minimum of difficulty and effort and yet which will, at the same time, be securely retained in related assembly with the background of the sign.

An additional object is the provision of such a sign wherein the letters may be arranged in such manner as to provide words reading horizontally, vertically, or diagonally as desired.

A still further object resides in the provision of such a sign which will be durable in construction, simple in operation, and relatively economical to manufacture.

Other objects will in part be obvious and in part be pointed out herein.

In the accompanying drawing, wherein there is shown a preferred embodiment of this inventive concept—

Figure 1 is a front elevational view of one form of sign embodying this invention.

Figure 2 is a bottom elevational view of the sign shown in Figure 1, certain parts thereof being shown in dotted lines and certain other parts thereof being broken away.

Figure 3 is an enlarged perspective view of the retaining strip for the letters comprising a feature of this invention.

Figure 4 is an end elevational view of one letter adapted for use with the sign.

Figure 5 is an enlarged perspective view of a letter also adapted for use with the sign; and

Figure 6 is a sectional view taken substantially along the line 6—6 of Figure 1 as viewed in the direction indicated by the arrows.

Like reference numerals refer to like parts throughout the several views of the drawing.

Having particular reference now to Figure 1, there is generally indicated at 10 a base or backing plate, forming the background of the sign, and provided with a plurality of rows of holes 11, arranged so as to be both vertically and horizontally aligned, such arrangement resulting automatically in diagonal alignment of the holes in adjacent rows. As best shown in Figure 6 grooves or recesses 12 adapted to contain suitable nuts or plates having threaded apertures therein are positioned in the rear face of the sign, the threaded apertures being in alignment with each of the holes 11.

The reading matter of the sign is portrayed by 55

letters, figures or other characters, representative specimens of which are designated by the reference character 13. The characters 13 are of a substantial thickness and have one or more apertures 14, according to the configuration of the character, passed laterally therethrough from side to side. Letters 13 are adapted to be positioned on bars 15, and suitably arranged and spaced thereon to spell out a requisite reading matter. Each of bars 15, which may be made of varying lengths to accommodate varying lengths of words, is provided with a plurality of apertures 16 therethrough, the apertures being so spaced as to coincide with the spacing of holes 11 in background 10. It may here be pointed out that the horizontal and vertical spacing of holes 11 is such that the distances therebetween are either equal, both horizontally and vertically, or one of such distances comprises a multiple of the other 20 distance in order that the same strip may be used for all straight lines either vertically or horizontally. Of necessity, different strips having holes spaced a different distance apart are utilized when it is desired to arrange the wording of the 25 sign along the diagonal lines between the holes in backing or supporting plate 10. In the operation of the device suitable strips 15 are first selected and the desired characters mounted thereon in the desired arrangement by passing strips 15 through apertures 14. The strips and their associated letters are then positioned in suitable alignment on background 10, and secured in place by screws 18 which pass through selected holes 16 and holes 11, and threadedly engaging the 30 threaded apertures in members 12 to secure the parts in related assembly. When it is desired to change the sign screws 18 are released and strips 15 removed. The same strips, or others having suitable rearranged wording thereon are then reassembled to the background 10 in the manner 35 previously described.

Letters 13 and background 10 as well as strips 15 may be made of any desired material, as for example, plastic, metal or wood, and the parts 40 may be of any desired size from a small window display, for example, to a roadside bill board. It is preferable that the letters and the background be of contrasting colors to enhance visibility, but any desired color or scheme of decoration 45 may be used for either the background or the letters, it being noted, however, that the strips 15 should be preferably of a transparent material such as plastic in order to minimize the visibility of such strips.

From the foregoing it will now be seen that

there is herein provided a device achieving all the objects of this invention and others, including many advantages of great practical utility and commercial importance.

As many embodiments may be made of this inventive concept and as many modifications may be made in the embodiment hereinbefore shown and described, it is to be understood that all matter herein is to be interpreted merely as illustrative and not in a limiting sense.

I claim:

1. In a sign, the combination of a base having a plurality of vertical and horizontal rows of holes therethrough, characters having transverse apertures therethrough, strips adapted to slide within and through said apertures to form a mounting for said characters, said strips having a plurality of holes therein so spaced as to coincide with said first-mentioned holes, and means, coacting with said holes for securing said strips to said base.

2. In a sign, the combination of a base having a plurality of vertical and horizontal rows of holes therethrough, characters having transverse apertures therethrough, strips adapted to slide within and through said apertures to form a mounting for said characters, said strips having

5 a plurality of holes therein so spaced as to coincide with said first-mentioned holes, members having threaded apertures therethrough positioned on the back of said plate adjacent each of said holes through said plate, said apertures being in registry with said holes, and means comprising screws to pass through selected first and second-mentioned holes and threadedly engaging said apertures to secure said strips to said base.

10 3. In a sign, the combination of a base having a plurality of vertical and horizontal rows of holes therethrough, members having threaded apertures therethrough positioned on the back of said base adjacent each of said holes, said apertures and said holes being in registry, strips having a plurality of holes therein so spaced as to coincide with said first-mentioned holes and hence said apertures, characters adapted to be secured to said strips and means coacting with said first- and second-mentioned holes and said apertures in said members for securing said strips to said base, said last-mentioned means comprising screws passed through selected first and second-mentioned holes and engaging selected threaded apertures.

25 HERBERT A. HOAG.
